United States Patent Office

Des. 209,504
Patented Dec. 12, 1967

209,504

RESTAURANT

Bobby L. Guy, Raleigh, N.C., assignor to Pik-A-Pak
Package Stores, Inc., Goldsboro, N.C., a corporation of North Carolina

Filed May 10, 1967, Ser. No. 7,056

Term of patent 14 years

(Cl. D13—1)

The dominant features of my design reside in the portions shown in full lines.

I claim:

The ornamental design for a restaurant, substantially as shown and described.
